DESIGN FOR A FOOD BROILER

Arthur A. Stone, Cleveland Heights, Ohio, assignor to Irwin M. Stone and Martin C. Friedman, both of Cleveland Heights, Ohio

Application January 27, 1934, Serial No. 50,523

Term of patent 14 years

To all whom it may concern:

Be it known that I, ARTHUR A. STONE, a citizen of the United States, residing at Cleveland Heights, in the county of Cuyahoga, and State of Ohio, have invented a new, original, and ornamental Design for a Food Broiler, comprising a drip pan member and a food supporting plate member mounted thereon, of which the following is a specification, reference being had to the accompanying drawing, forming part thereof.

In said drawing, Fig. 1 is a plan view of a food broiler, showing my new design; and Fig. 2 is a cross sectional view thereof on the line 2—2, Fig. 1.

I claim:

The ornamental design for a food broiler, as shown and described.

ARTHUR A. STONE.
